CLAIM

The ornamental design for a dermal spray apparatus, as shown and described.

DESCRIPTION

FIG. 1 is a perspective view of top, front, and right sides of a dermal spray apparatus showing our new design;

FIG. 2 is a perspective view showing top, front, and left sides thereof;

FIG. 3 is a front elevation view thereof;

FIG. 4 is a back elevation view thereof;

FIG. 5 is a left side elevation view thereof;

FIG. 6 is a right side elevation view thereof;

FIG. 7 is a top plan view thereof; and,

FIG. 8 is a bottom plan view thereof.

The broken lines depict portions of the dermal spray apparatus that form no part of the claim.

1 Claim, 8 Drawing Sheets(56)
